UNITED STATES PATENT OFFICE.

CHARLES WEINEDEL, OF LOUISVILLE, KENTUCKY, ASSIGNOR OF ONE-THIRD
TO OTTO E. MUELLER, OF SAME PLACE.

WATCHMAN'S TIME-DETECTOR.

SPECIFICATION forming part of Letters Patent No. 510,745, dated December 12, 1893.

Application filed December 20, 1892. Serial No. 455,765. (No model.)

To all whom it may concern:

Be it known that I, CHARLES WEINEDEL, a resident of Louisville, in the county of Jefferson and State of Kentucky, have invented certain new and useful Improvements in Watchmen's Time-Detectors; and I do hereby declare the following to be a full, clear, and exact description of the invention, such as will enable others skilled in the art to which it applies to make and use the same.

My invention relates to an improvement in watchman's time detectors,—the object being to construct the device in such manner that it shall be adapted to be operated by the watchman at certain predetermined intervals of time and so that it cannot be operated until a given interval of time shall have expired.

A further object is to construct a watchman's time detector in such a manner that the instrument itself will indicate whether or not it has been properly operated and so that at each operation of the instrument the number of the instrument will be recorded at a central office.

25 A further object is to construct the device in such manner that it cannot be tampered with by the watchman.

With these objects in view the invention consists in certain novel features of construction and combinations and arrangements of parts as hereinafter set forth and pointed out in the claims.

In the accompanying drawings: Figure 1 is a face view of the device. Fig. 2 is a face view with the casing removed. Fig. 3 is a view illustrating the means for stopping the clock movement, and showing the parts in position to operate the signaling devices. Fig. 4 is a separate view illustrating the clock 35 starting mechanism. Figs. 5, 6, 7, 8 and 9 are detail views. Fig. 10 is a view in side elevation, the casing being shown in section.

A represents a back or base plate to which the mechanism hereinafter described is attached, said mechanism being inclosed by a casing B fixed to the back or base plate A and having a glass front C through which the indicators can be read. This case is permanently secured to the back or base plate A and is not to be removed by the watchman 45 who operates the device, thus preventing the

watchman from tampering with the device and sending in false signals. A clock movement D is secured to the back plate A and in its structure comprises a wheel or pinion *a* 55 adapted to make one revolution in one hour. It also comprises a wheel or pinion *b* adapted to make one revolution in, preferably, twenty-four hours.

Mounted loosely on the shaft *a'* of the wheel or pinion *a* and adapted to be carried by and rotated with the wheel *b*, is a disk *c*, having a single tooth *c'*. A notched disk *d* is revolvably mounted below the disk *c* and has produced in its face a series of numbers from 1 to 7 inclusive, said numbers representing the days of the week. The tooth *c'* is adapted to mesh with the notched disk *d* at each revolution of the disk *c*, and said disk making one revolution in twenty-four hours it will be seen that the numbered disk *d* will be moved one notch every twenty-four hours.

Secured to the arbor *e* of the spring *e'*, is a collar *e''* from which an L-shaped arm *e''* projects, the free or bent end of said arm being 75 adapted to engage pins *e''* projecting from the wheel or pinion *a*, the clock mechanism being so timed that one of the pins *e''* will reach a point over the shaft of the pinion *a* at the same time that the free end of the arm *e''* reaches the same point and thus stop the clock movement. The pins *e''* will preferably be arranged at diametrically opposite points on said wheel so that the wheel, and consequently the whole clock movement, will be 80 stopped once every half hour. It is evident however, that only one pin *e''* may be employed so as to cause a stoppage of the movement once every hour,—or more than two pins may be employed so as to cause the 85 movement to stop oftener than once every half hour. An arm *f* is secured to and projects laterally and normally slightly upwardly from the arbor *e*. To the outer end of the arm *f*, a pitman *f'* is pivotally connected, 90 which pitman extends downwardly and at its lower end is pivoted eccentrically to a disk *g*, which latter is loosely mounted on an arbor *g'* supported by a frame *g''*. A sleeve *g''* projects from the center of the disk *g* and is 95 adapted to receive the end of said arbor *g'*—the free end of said sleeve being preferably

closed and adapted to receive a crank arm h , said crank arm being secured to said sleeve by means of a pin h' . From this construction it will be seen that when the disk g is 5 partially rotated the spring e' will be partially wound, through the medium of the arm f and pitman f' , and the L-shaped arm e^3 will be carried away from the pins e^4 carried by the wheel or pinion a . When the disk g is 10 thus partially rotated the L-shaped arm e^3 will be carried from the pins of the wheel a far enough so that the running of the clock movement for a half hour will bring it back again in alignment with the pins e^4 so that its 15 engagement with one of them will cause the clock mechanism to stop. From this it will be seen that it is necessary for the watchman to operate the device once every half hour.

A collar i is carried by the disk c and adapted 20 to embrace this collar is a hand or pointer i' , which registers with figures on a dial i^2 . The figures on the dial will preferably range from one to twenty four, thus representing twenty-four half hours,—or, when the device 25 is adapted to be operated once every hour, the figures will represent twenty-four hours.

A spring j is connected at one end to the shaft or arbor g' and at the other end to a pin j' projecting from the frame g^2 . A gear 30 wheel k is loosely mounted on the shaft or arbor g' and carries a pivoted dog k' , adapted to engage a ratchet wheel k^2 secured to the shaft or arbor g' , a spring k^3 secured to the wheel k being employed to retain the dog in 35 engagement with said ratchet wheel. The gear wheel k is adapted to mesh with a pinion l carried by an arbor l' . The arbor l' also carries a spur wheel l^2 which meshes with a pinion l^3 carried by an arbor l^4 . The arbor l^4 40 also carries an escapement wheel l^5 with which an escapement pawl l^6 engages, said escapement pawl having a weighted arm l^7 secured thereto to insure its proper operation. A disk m is secured to the arbor l' and is provided 45 on its periphery with teeth or projections m' . An insulating block m^2 is secured to the frame g^2 , and to this insulating block a spring n is secured and adapted to be engaged by the teeth or projections m' on the disk m . The disk m and spring n are included 50 in an electric circuit indicated by the wires o, o' , said electric circuit extending to a central station where it includes an instrument of suitable construction. From this 55 construction it will be seen that when the disk m is permitted to rotate by the operation of the device the projections m' will successively engage the spring n and thus make and break the electric circuit, and thus cause the instrument at the central office to report the 60 number of the box operated.

A lever p is pivotally connected to the under side of the disk g , and is provided with an arm p' which, when the parts are in position to be operated, engages a spring p^2 secured to the frame g^2 . The lever p is guided 65 in its movements by means of a pin p^4 pro-

jecting through an elongated slot p^5 in the disk g . On the inner face of the lever p a shoulder q is formed, with which an arm q' 70 projecting from a collar q^2 fixed on the shaft or arbor g' is adapted to engage when the parts are in position to be operated. An arm r projects from the collar q^2 and is preferably made in the form of a segment. At one end 75 of the segmental portion of the arm r is a projection r' , with which a pin r^2 on the make and break disk engages to limit the movement of said disk. In order to relieve the strain on the pin r^2 by its constant and sudden engagement with the arm r , a spring or yielding device s is secured to the frame g^2 and adapted to receive the end of the projection r' of the arm r , said projection reaching the spring s slightly in advance of the pin r^2 on the make 80 and break disk.

Now let it be supposed that the clock movement has been brought to a standstill and the operator wishes to manipulate the device. He grasps the crank arm h and causes a partial revolution of the disk g . By this movement of the disk the spring of the clock movement will be partially wound up and the arbor e to which said spring is attached will be rotated thus raising the arm e^3 out of engagement with pin e^4 and thereby release the clock work. When the disk g is in position to be operated (and before it is rotated as above mentioned) the spring p^2 is in engagement 90 with the arm p' of the lever p and retains the shoulder q in engagement with the arm q' projecting from the collar q^2 . Now, suppose the disk to be partially rotated as above described. It will be seen that the clock movement will be set free as above mentioned and 95 that the shaft or arbor g' will be rotated and the spring j wound up. When the disk shall have been rotated sufficiently the end of the lever p will engage a stop t supported by the frame g^2 and thus be moved away from the 100 arm q' ,—thereby releasing the spring j and the parts which it actuates. Thus it will be seen that the make and break mechanism will be set in motion and the signal “turned in.” The clock movement will now continue its 105 operation and as it operates the disk d will be moved slowly to the starting point, at which time the clock movement will be again stopped.

A sliding bar u is connected to one side of the frame of the clock-movement and provided with elongated slots u' for the passage of the pins or screws which support it. An arm u^2 projects downwardly from the sliding bar u and at its lower end is bent so as to lie 110 normally in the path of a pin u^3 projecting from the under face of the disk d . In proximity to the upper end of the sliding plate u , a spring arm u^4 is secured, which is designed, 115 when the sliding plate u is raised to raise the tail of a lever u^5 , the head of which is notched as at u^6 to engage a tooth or projection u^7 on the hub of the balance wheel, thereby starting 120 the movement. Thus it will be seen that

when the device is operated to set the make and break mechanism in motion, the pin u^3 projecting from the disk will strike the arm u^2 of the sliding plate u and thus start the 5 clock movement.

In operating the device, the watchman will grasp the crank arm h and cause a partial revolution of the disk g . The disk g being connected with the winding arbor of the 10 clock movement, by the pitman f' and arm f , when the disk g is turned as above explained, the winding arbor will also be turned and thus the spring of the clock movement will be wound. When the winding arbor is thus 15 turned, the end of the L-shaped arm e^3 will be moved up, out of engagement with the pin e^4 projecting from the wheel or pinion a , thus releasing the clock movement. When the disk is turned by the watchman as above explained, the pin u^3 on the disk g will strike the arm u^2 projecting from the bar u and cause an upward movement of the latter. When the bar u moves up, the spring arm u^4 carried thereby, will strike the escapement lever u^5 and set the clock movement in motion. 20 The clock movement will run for one-half hour, when it will be stopped by the engagement of the L-shaped arm e^3 with one of the pins e^4 on the pinion a . During the operation 25 of the clock movement, the pointer i' will move from one figure on the dial i^2 to another, the figures on said disk counting, as above stated, by half-hours. At each revolution of the disk c on the shaft a' , the tooth c' on said disk will engage one of the notches in the disk d and cause a movement thereof,—the figures on said disk indicating the days of the week, as above described.

When the disk g is turned to produce the 40 operation of the clock movement above mentioned, other devices will be set in motion, whereby to operate electrical signaling mechanism, the operation of which mechanism is as follows: When the disk g is turned by the 45 watchman, the arm q' carried by the shaft or arbor g' will engage the shoulder q on the lever p and thus cause said arbor to move with the disk g and wind the spring j , the shoulder q of said lever p being retained normally 50 in engagement with the arm q' by means of the spring p^2 . When the disk g and its arbor g' shall have been moved to a sufficient extent, the forward end of the lever p will engage the pin or stop t and by it will be moved 55 out of engagement with the arm q' , thus releasing the arbor g' from the disk g , whereupon said arbor will be rotated by the spring j and cause the operation of the electrical make-and-break mechanism, in a manner 60 which will be presently explained. The disk g will be returned to its normal position by means of the clock movement, through the medium of its connection therewith and when it reaches its normal position (which requires 65 a half hour), the shoulder on the lever p will again engage the arm q' . Thus it will be seen

that the device cannot be operated oftener than each half hour. In other words the watchman cannot turn in the signal before the prescribed half hour has expired. When the 70 arbor g' and the disk propelled thereby have been rotated sufficiently by the spring j , they will be stopped by the engagement of the segmental arm r with the pin r^2 . In order to prevent the breakage of the pin r^2 by the sudden or abrupt engagement of the segment r , the spring arm or yielding device s is employed.

When the shaft g' is rotated by the spring j as above explained, motion will be imparted, 80 through the gearing above described, to the make-and-break disk m , causing its teeth or projections m' to ride over the spring n and thus make and break the electrical circuit which includes said disk and spring,—thereby 85 operating the signaling apparatus located at a central station.

From the construction and arrangement of parts as above described it will be seen that it will be impossible for a watchman to operate the device until a certain predetermined time has expired. The hand or pointer i' will indicate the number of signals turned in, which will prevent watchmen and operators at the central station from working together 90 and giving false reports. The report coming in from the central office must tally with the indicator on the time movement. By this means a report is had from the clock movement and also from the central office, thereby 95 watching both watchman and operator at the central station. In a building where a number of time detectors are employed, it is not necessary to provide more than one with the make and break mechanism, as all the indicators must tally with the one having the 100 make and break mechanism.

Various slight changes might be made in the details of construction of my invention without departing from the spirit thereof or 110 limiting its scope, and hence I do not wish to limit myself to the precise details of construction herein set forth, but,

Having fully described my invention, what I claim as new, and desire to secure by Letters 115 Patent, is—

1. In a watchman's time detector, the combination with a clock movement and make and break devices, of means independent of the make and break devices for automatically 120 stopping said clock movement at certain predetermined times, and means for simultaneously releasing said clock movement and make and break devices, substantially as set forth.

2. In a watchman's time detector, the combination with a clock movement and circuit make and break devices, of means independent of the make and break devices for automatically stopping said clock movement at 130 certain predetermined intervals, means for releasing said clock movement and the make

and break devices simultaneously and means for starting the clock movement, substantially as set forth.

3. In a watchman's time detector, the combination with the winding or spring arbor of a clock movement, and an arm carried by said arbor, of pins projecting from one of the wheels of the clock movement and adapted to engage said arm, another arm projecting from said arbor, a pitman pivotally connected at one end to said last-mentioned arm, and an oscillatory disk to which the other end of said pitman is eccentrically pivoted and a crank arm for operating said disk, whereby to partially wind the spring of the clock movement and release the same, substantially as set forth.

4. In a watchman's time detector, the combination with a clock movement, an oscillatory disk, a connection between said disk and the winding arbor of the clock movement, an arbor on which said disk is mounted, a spring connection with said arbor, make and break devices, mechanism between said arbor and 25 make and break devices whereby motion is imparted by said spring from said arbor to the make and break devices, a pivoted lever carried by said disk, an arm carried by the arbor and adapted to engage a shoulder on 30 said pivoted lever, a spring for insuring the engagement of said arm and lever, and a stop or projection with which said pivoted lever is adapted to make contact when the disk is oscillated and move said lever out of contact 35 with said arm, and thus release the make and break mechanism without causing the return movement of the oscillatory disk, substantially as set forth.

5. In a watchman's time detector, the combination with a clock movement and an oscillatory disk, of a connection between the winding arbor of said clock movement and the oscillatory disk, an arbor on which said disk is loosely mounted, a spring for causing 40 a rotation of said arbor, a disk having a series of projections on its periphery, mechanism

for imparting motion from said arbor to said disk, a spring adapted to be engaged by the projections or teeth on said disk, an arm carried by said arbor, and a pin on the toothed disk adapted to engage said arm and limit the movement of the toothed disk, substantially as set forth. 50

6. In a watchman's time detector, the combination with a clock movement and an oscillatory disk, of a connection between the winding arbor of said clock movement and the oscillatory disk, an arbor on which said disk is loosely mounted, a spring for causing a rotation of said arbor, a disk having a series 60 of teeth or projections on its periphery, mechanism for imparting motion from said arbor to said toothed disk, a spring adapted to be engaged by the projections or teeth on said disk, an arm carried by said arbor, a pin on the toothed disk adapted to engage said arm and limit the movement of the toothed disk, and a spring adapted to receive and cushion 65 the free end of said arm, substantially as set forth. 70

7. In a watchman's time detector, the combination with a clock mechanism and a make and break mechanism, of an oscillatory disk, a connection between the winding arbor of the clock movement and said oscillatory disk, 75 means connected with said disk for operating the make and break mechanism, a sliding bar, a lever actuated by the escapement mechanism of the clock movement, a spring arm carried by the sliding bar and adapted to engage 80 said lever when the bar is raised and thus start the clock movement, and a pin on said oscillatory disk adapted to engage the sliding bar to raise it, substantially as set forth.

In testimony whereof I have signed this 85 specification in the presence of two subscribing witnesses.

CHARLES WEINEDEL.
